UNITED STATES PATENT OFFICE.

JOHN EDWARD THORNTON, OF LONDON, ENGLAND.

APPARATUS FOR PRINTING CINEMATOGRAPH-PILOTS.

1,158,587.

Specification of Letters Patent.

Patented Nov. 2, 1915.

Application filed April 18, 1914. Serial No. 882,899.

To all whom it may concern:

Be it known that I, JOHN EDWARD THORNTON, a British subject, residing at London, England, have invented certain new and useful Improvements in Apparatus for Printing Cinematograph-Films, of which the following is a specification.

This invention relates to apparatus for printing a narrow cinematograph film of a low degree of sensitiveness such as sensitized with bichromated gelatin.

In my prior application Serial No. 745725, filed February 1, 1913, a machine with a drum or wheel of large diameter and slow rotary movement is described, the narrow sensitized film to be printed being passed over it and the negative clamped in close contact therewith by a transparent endless band the two films as the drum rotates being passed around it and subjected to the action of a narrow streak of light of high actinic and low heating power placed longitudinally of the film.

The invention consists in the substitution on the former machine for a single transparent pressure band to clamp the negative and sensitized films in close contact during printing, of two pressure bands either opaque or transparent to grip the margins or edges of the narrow films to hold them in contact leaving a narrow uncovered gap or space between the bands through which the narrow streak of light can pass for printing.

The invention will be fully described with reference to the accompanying drawings.

Figure 1 is a sectional elevation of the machine. Fig. 2 is a plan. Fig. 3 is a transverse section of a portion of the drum enlarged. Fig. 4 is a transverse section of a portion of the drum enlarged, showing the addition of an air trunk. Fig. 5 is an elevation of a modification of the film reel showing tension device applied thereto. Fig. 6 is an elevation of tension rollers for applying tension to the films as they are passed forward to the drum. Fig. 7 is a transverse section of a portion of the drum A showing a modified form of the endless pressure band. Fig. 8 is a similar view showing a further modification of the pressure band.

The drum A with a ring of mercury vapor lamps C placed longitudinally around the periphery and either with or without an

air duct D is similar to that described in Thornton's application Serial No. 745725.

Around the periphery of the drum A two endless pressure bands B B' are passed guided by suitable guide rollers b to grip the margins or edges of the negative film G as it is passed over the drum in contact with the sensitized film F. The bands are maintained at the desired tension by a weighted guide roller b' mounted on an arm i pivotally mounted on the shaft l', and clamp the two films in contact as they pass around the drum A.

The pressure bands B B' may be opaque and made of rubber, leather, woven fabric, metal or other flexible material or they may be transparent of any suitable material. In use opaque bands prevent the light acting upon the margins of the films and with certain printing processes leave the print with opaque margins. Transparent belts on the other hand allow the light to reach the margins of the films yielding clear margin prints. Their use also permits of the publisher's name or other matter being printed along the margin of the film by first printing it along the margin of the negative film or along the edge of one or both of the transparent pressure bands such matter being reproduced upon the sensitive films during exposure to light.

The periphery of the drum A may be flat or more or less convex with a curved pad or cushion a of plush, rubber or other slightly yielding material to insure perfect contact between the negative and sensitive films.

The sensitized film F is taken from a reel f in the usual way and when printed after passing around the drum is wound onto a similar reel f' and the negative film G is taken from a reel g and rewound onto a reel g'.

Around the drum A and between the lamps C and the films F and G there is fitted a grid M' composed of thin metal plates set radially with spaces between to cause the light rays from the lamps to strike the film perpendicularly.

To prevent slackness or sagging of the films, they pass from the reels f and g over two pneumatic suction boxes L, L', as shown in Fig. 1, or a tension or friction device H is applied to the reels f and g (see Fig. 5) or a pair of tension rollers K K' may be

placed adjacent to the reels *f* and *g* between which the films are drawn as they pass from the reels to the drum see Fig. 6. Such devices prevent any slackness or unevenness in the winding of the films on the reels interfering with the close contact of the films upon the drum *A*.

If desired, the pressure bands *B* *B'*, as shown in Fig. 7, may have a rib or ribs *N* 10 on the under side and the face of the drum be grooved to guide and maintain the bands in the proper position on the drum, or these pressure bands may be provided with perforations *O*, as shown in Fig. 8, engaging 15 with sprocket teeth *o*, by which they may be driven, instead of by friction.

A motor *M* drives the drum *A* by a cord or rope *m* in a groove *a'* in the periphery and the reels *f'* *g'* by cords *m'* passing over 20 pulleys on the reel spindles.

What I claim as my invention and desire to protect by Letters Patent is:—

1. In apparatus for printing cinematograph films comprising a large drum around 25 the periphery of which the films are passed and mercury vapor lamps placed longitudinally of the film, the combination of two pressure bands—operative—to grip the margins or edges of the films and clamp them 30 to the drum leaving the film between them exposed to the action of a narrow streak of light of high actinic and low heating power from said lamps substantially as described.

2. In apparatus for printing cinematograph films comprising a large drum around 35 the periphery of which the films are passed and mercury vapor lamps placed longitudinally of the films, the combination of two pressure bands—operative—to grip the margins or edges of the films and clamp them 40 to the drum leaving the film between them exposed to the action of a narrow streak of light of high actinic and low heating power from said lamps and a curved pad around 45 the periphery of the drum operative to give a transverse bend to the films for the purpose of insuring perfect contact between

both films as they are curved longitudinally and carried around the periphery of the drum.

3. In apparatus for printing cinematograph films comprising a large drum around the periphery of which the films are passed and mercury vapor lamps placed longitudinally of the films, the combination of two 55 pressure bands—operative—to grip the margins or edges of the films and clamp them to the drum leaving the film between them exposed to the action of a narrow streak of light of high actinic and low heating 60 power from said lamps, and a tension device operative to prevent slackness in the films as they are drawn forward by the drum.

4. In apparatus for printing cinematograph films the combination with a rotating printing drum having a pair of pressure belts to clamp the strips thereto, and means for producing a streak of cool actinic light encircling the drum, of an air trunk encircling the drum for conducting a blast of filtered air passing therethrough to remove the surplus heat.

5. In apparatus for printing cinematograph films comprising a large drum around 75 the periphery of which the films are passed and mercury vapor lamps placed longitudinally of the films, the combination of two pressure bands—operative—to grip the margins or edges of the films and clamp them 80 to the drum leaving the film between them exposed to the action of a narrow streak of light of high actinic and low heating power from said lamps and a grid comprising a number of thin plates to cause the light rays 85 to strike the film perpendicularly.

In testimony whereof I have hereunto set my hand in presence of two subscribing witnesses.

JOHN EDWARD THORNTON.
